Fig. 5

FIGURE 1 is a front perspective view of a photocopying apparatus showing my new design;

FIGURE 2 is a rear elevational view thereof;

FIGURE 3 is a front elevational view thereof;

FIGURE 4 is a side elevational view of the side opposite that shown in FIGURE 1; and

FIGURE 5 is a front perspective view of a second embodiment of my design wherein the side vents are provided with louvered openings and the top is provided with a fan housing at rear center.

This application is a continuation-in-part of my co-pending application Serial No. D. 78,675, filed on February 18, 1964, and now abandoned.

I claim:

The ornamental design for photocopying apparatus, substantially as shown and described.
